UNITED STATES PATENT OFFICE

FRANK ALBACH, OF ST. LOUIS, MISSOURI, ASSIGNOR TO FRED MEDART MANUFACTURING COMPANY, OF ST. LOUIS, MISSOURI, A CORPORATION OF MISSOURI

BASKET-BALL BACKSTOP

Application filed June 1, 1931. Serial No. 541,846.

This invention relates generally to basket-ball back-stops and has particular reference to a foldable frame for basket-ball back-stops of swing-up type.

5 My invention has for a prime object the provision of a basket-ball back-stop including a conveniently and easily operable foldable frame for firmly, rigidly, and efficiently supporting the back-stop in playing position, the frame being, however, readily foldable or swingable for withdrawing the back-stop from playing position to elevated or retracted position for thereby releasing the basket-ball playing field for other purposes.

10 And with the above and other objects in view, my invention resides in the novel features of form, construction, arrangement, and combination of parts hereinafter described and pointed out in the claims.

15 In the accompanying drawings,—

Figure 1 is a side elevational view of one form of basket-ball back-stop embodying my invention, the apparatus being shown in full lines in lowered playing position and in dot-dash lines in retracted or swung-up, non-playing position, the main frame being fragmentally shown and the near rail thereof broken away at the center for illustrating the back-board-frame-hanger;

20 Figure 2 is an enlarged detail view of a portion of the apparatus, illustrating the means for latching the back-board frame in playing position;

25 Figure 3 is a fragmentary approximately half rear view of the apparatus;

Figure 4 is an enlarged rear view, partly in section, of the parts shown in Figure 2;

Figure 5 is a detail view, partly in section, of one of the back-board frame hangers;

30 Figure 6 is a side elevational view of another form of basket-ball back-stop embodying my invention, the apparatus being shown in lowered playing position;

Figure 7 is an enlarged detail broken view, 35 partly in section, of a portion of the apparatus of Figure 6, illustrating the means for latching the back-board frame thereof in playing position.

Figure 8 is a fragmentary approximately half rear view of the apparatus of Figure 6;

Figure 9 is an enlarged rear view, partly in section, of the parts shown of Figure 8;

Figure 10 is an enlarged fragmental broken view, partly in section, of the latch releasing mechanism; and

Figure 11 is a transverse sectional view approximately on the line 11—11, Figure 10.

Referring now more in detail and by reference characters to the drawings, which illustrate practical embodiments of my invention, I may first state, briefly, that the back-stop A or A' comprises, as is customary in apparatus of the present general type, a substantially rectangular board 1 for presenting,

when lowered and in playing-position, a 65 plane surface toward the playing-field and preferably having on its rear side suitable reinforcing side rails 2, end rails 3, and stiffening members 4, as best seen in Figure 3. Fixed to, and projecting forwardly from the 70 front face of, the back-board 1, is the usual basket-ring 5 with its supported basket-net 6.

75 My present invention is directed to apparatus for supporting the back-stop A or A', such apparatus including either a swingable frame B or B' carrying the back-stop A or A' and a co-operable back-brace C or C' for rigidly supporting the frame B or B' with the backstop A or A' in proper playing position.

80 Either form of such apparatus is preferably suspended from an elevated support or main frame, which may be a part of a building structure, part of an outdoor framework, or the like, suitably adapted for use with my invention, as may best serve the purpose at hand. Preferably, however, such support includes a pair of spaced parallel substantially horizontal preferably tubular longitudinal 90 rails or pipes D, which may, as has been stated, be supported conveniently in any one of several ways according to the circumstances peculiar to the locality of use and, hence, not deemed necessary of more complete description here.

95 Referring now to the form of the apparatus illustrated in Figures 1 to 5, both inclusive, disposed in suitably spaced relation, and rigidly supported, as by suitable saddles 7 and 100

co-operating clamping-caps 8, along the rails D, is a plurality, preferably three, transverse or cross beams or pipe-bars 9, 10, and 11; and suitably secured, as by respective caps 12, in spaced relation on the middle cross-bar 10 intermediate the rails D, is a pair of suitable hangers 12, each including a depending bifurcated extension 13 supporting a transverse pin 14, on which is pivoted for swingable movement an eye 15 provided with a pair of spaced depending plates 16. Having their respective upper ends disposed between, and as by suitable fastening elements or bolts 17 fixed to, the respective pairs of depending plates 16, is a pair of suspended correspondingly transversely spaced I-beams 18, which form part of the back-stop frame B. The beams 18 at their opposed flanges are parallel with, and operatively disposed to the rear of, the board 1, and suitably clamped on the beam front flanges 20 and having ears 21 fixed by fastening elements 22 to board 1, are brackets 19 for securing the beams 18 to the board 1. Connecting the rear flanges 23 of the I-beams 18, is a transverse preferably angle or inverted L-shaped member 24 disposed slightly above the plane of the top edge of the board 1, as best seen in Figure 3.

Also mounted on, and residing against the face of, the rear flanges 23 of the respective beams 18 adjacent the lower margin of the board 1 in transverse registration, is a pair of keeper-brackets 25, which preferably are secured adjustedly to the flanges 23 as by means of retaining members 26 clampingly engaged with the sides of the respective flanges 23 and fixed to the body of the bracket 25 by means of fastening elements or bolts 27 passed through the keeper-body.

Journalized for oscillatory movement in and through the webs of the respective keepers 25, and extending transversely between, and to the rear of, the I-beams 18, is a shaft 28.

Having their respective hubs 29 pinned, as at 30, to, and disposed adjacent the opposite ends of, the shaft 28, are latch-operative arms 31 for impinging, on oscillatory or rotatory movement of the shaft 28, respective pins 32 projecting laterally from latch-bolts 33 slidably disposed in ways 34 extending obliquely outwardly and downwardly in the respective brackets 25. Each way 34 in one wall thereof is provided with a slot, as at 36, in which the respective pin 32 may reciprocate or work, and disposed between the upper closed end of the way 34 and the inner end of the bolt 33, is a tensional member or coiled spring 35 for normally yieldingly urging or biasing the bolt 33 outwardly of the way 34 until stopped by the impingement of the pin 32 with the lower end wall of the slot 36, as best seen in Figure 2.

Provided upon the rear face of each respective bracket 25 with its upper wall tan-

gent to the end of the way 34, is a keeper-notch or seat 37 adapted to be overrun by the bolt 33 on extension thereof from the way 34 for latching, retaining in the transversely registering notches 37 a transverse bar 38 upon which the back-leg members 39 of the back-brace C, presently to be described, are at respective ends pivotally mounted and, as best seen in Figure 3, each latch-bolt 33 is formed at its outer end with a cam-face 40 adapted for engagement by the bar 38 for automatically latching the same in the notches 37.

The leg-members 39 of the frame C are disposed in spaced pair parallel relation and are preferably in the form of tubular pipe struts, each provided at its lower end with an eye-fitting 41 engaging reduced end sections 42 of the bar 38. At their respective upper ends, the back-legs 39 are each provided with an eye-fitting 43 pivotally engaging a pin 44 supported in the bifurcated depending portion of a bracket 45 saddled for engaging the rear transverse frame-member 9, a cap 46 being bolted to the bracket 45 for clamping the same to the pipe 8, as best seen in Figure 3, and it may be stated that the frame bar 8 is adjustably shiftably located on the longitudinal frame members D in such manner that the back-stop A will be vertically disposed when the back-brace bar 38 is latched in the keeper notches 37 of the back-stop frame B.

Having their respective lower ends pivotally mounted on the reduced end sections 42 of the bar 38 and disposed between the shoulders thereof and the eye-fittings 41, is a pair of links 47 whose respective upper ends are pivotally connected, as at 49, to bifurcated I-beam clamps 48 adjustably mounted on the rear flanges 23 of the I-beams 18 a suitable distance above the brackets 25, the links 47 thus permanently connecting the swingable ends of the frames B and C for supporting the lower end of the frame C when the back-stop frame B is raised or swung to retracted or elevated position and also for guiding the frame C properly for latching co-operation of the bar 38 with the keeper-notches 37 when the back-stop frame B is lowered to playing position, all as presently appearing.

It will be obvious, however, that the back-stop frame B may not be swung to elevated position until the bar 38 is unlatched from the brackets 25. For such purpose, on the cross-shaft 28 intermediate the brackets 25 is pinned or mounted a crank or arm 50, which, under the co-action of the biased pins 32 and the latch-arms 31 on corresponding rotatory movement of the shaft 28, is normally, as when the back-stop A is in playing position, obliquely rearwardly disposed, as best seen in Figure 2. At its free end, the arm 50 is provided with an eye 51 for receiving the bight of a pull-rope or cable 52 trained over

a fixed sheave or pulley 53 mounted in a bracket 54 supported on the cross-member 24. From the pulley 53, the cable 52 is trained over the swivel-pulley 55 suspended 5 from a clamp 56 attached to the front cross-frame-member 11, and from the swivel-pulley 55, the cable 52 may, for manual manipulation thereof, lead to any conveniently accessible locality for ready gripping engagement.

For laterally stiffening the frame B when in playing position, an eye-bolt 57 is fixed in the web of each I-beam 18 adjacent the lower end thereof, and attached to the eye-bolts 57 are suitable guy-cables 58 oppositely extending obliquely upwardly and outwardly to respective eye-clamp fixtures 59 mounted on the suitably extended ends of the middle cross-frame member 10. By suitably shifting the eye-bolts 57 on the frame member 10, the cables 58 may be adjusted so as to become taut as the back-board frame B is lowered to playing position, as best seen in Figure 3.

In use, when it is desired to raise or swing the back-stop A to elevated non-playing position, an initial pull on the cable 52 exerts a turning movement on the shaft 28, whereby the bolts 33 are withdrawn for unlatching the bar 38 from the brackets 25, thereby releasing the frame B for upward swinging actuation, accomplished by further pull on the cable 52, which pull is continued until the back-stop A is drawn to its elevated position, the several parts then taking the respective positions shown by dot-dash lines in Figure 1. On releasing the cable 52, the frame B and back-stop A may be readily lowered to playing position, the brace-frame C automatically latching itself in bracing position, as described.

I might add that the pivotal point of the brace frame C is at a lower elevation than the pivotal point of the back-board frame B; hence, if the pulley 55 be sufficiently elevated, the frames B, C, may readily be so folded as to cause the back-legs 39 to lie substantially flatwise against the I-beams 18, the entire apparatus then being substantially non-obstructive to any game played thereunder.

Referring now to the preferred form of the apparatus illustrated in Figures 6 to 11, both inclusive, suitably secured in spaced relation on the middle cross-bar 10' intermediate the rails D, is a pair of suitable hangers 12', to which are pivoted, as at 15', for swingable movement preferably arcuate links 16', to which, in turn, are suitably fixed 55 a pair of suspended correspondingly transversely spaced pipe-bars 18' forming part of the back-stop frame B' and whose respective lower ends are secured, as by means of brackets 19', to the board A'.

Fixed on the pipe-bars 18' slightly above

the plane of the upper margin of the board A', as best seen in Figure 8, are split-clamps or the like 60, and projecting inwardly in opposed relation from the clamps 60, are pipe-sections 61. Having its opposite ends seated in, and, as by cross-pins 62, fixed to, the pipe-sections 61, is a cross bar or tube 63, sleeved upon which for rotatory movement is a tubular member or bar 64. Formed in the bar 64 adjacent its opposite ends, are registering circumferential slots 65, fitting in which for limiting the rotatory movement of the sleeve-bar 64, are lugs or fingers 66 projecting radially from the supporting pipe-sections 61.

Suitably clamped or secured upon the rear face, and adjacent the lower margin, of the board A in transverse registration, is a pair of keeper-brackets 25', and slidable in ways 34' extending outwardly and downwardly in the respective brackets 25', are latch-bolts 33'. Each way 34' is provided in a wall thereof with a slot, as at 36', in which lateral pins 32' on the bolts 33' may reciprocate or work for limiting the slidable movement of the bolts 33'. Each bolt 33' is provided, for purposes presently appearing, with an extension 67 projecting outwardly through the otherwise closed upper end of the way 34', and disposed between the upper closed end of the way 34' and the inner end of the bolt 33', is a tensional member or coiled spring 35' for normally yieldingly urging or biasing the bolt 33' outwardly of the way 34' until stopped by engagement of the pin 32' 100 with the lower end wall of the slot 36', as best seen in Figure 7.

Provided on the rear face of the respective brackets 25', with its upper wall tangent to the end of the way 34', is a keeper-notch or seat 37' adapted to be overrun by the bolt 33' on extension thereof from the way 34' for latchingly retaining in the transversely registering notches 37' a transverse bar 38' upon which in like manner are pivotally connected the back-leg members 39' of the back brace C', which latter is substantially similar in structure, function, and operation to the back-brace C and substantially in like manner hingedly attached to the board A'; hence, to avoid repetition further detail description thereof is omitted.

It will again be obvious, however, that the back-stop frame B' may not be swung to raised or elevated position until the bar 38' 120 is unlatched from the brackets 25'. For such purpose, on the cross-shaft or sleeve 64 intermediate the ends thereof is pinned or otherwise fixed a crank or arm 50', which normally, as when the back-stop is in playing position, is rearwardly disposed, as best seen in Figure 7. At its free end, the arm 50' is provided with an eye 51' for receiving the bight 125 of a pull-rope or cable 52' trained over a swivel-pulley 55' suspended from a clamp 56' 130

attached to the front cross-frame-member 11, and from the swivel-pulley 55', the cable 52' may, for manual manipulation thereof, lead to any conveniently accessible locality for ready gripping engagement. And attached at one end to respective eyes 68 on the bolt-extensions 67 and at its other end, as best seen in Figures 7 and 8, suitably fixed to, and adjacent the opposite ends of, the rotary cross-sleeve 64, are connecting cables or other flexible members 69.

Hence, in use, when it is desired to raise or swing the back-stop A' to elevated, non-playing position, an initial pull on the cable 52' exerts a turning movement on the sleeve 64, whereby, in turn, the cables 69 are wound on the sleeve 64 and the bolts 33' thereby withdrawn for unlatching the bar 38' from the brackets 25' and releasing the frame B' for upward swinging actuation, accomplished by further pull on the cable 52', which pull is continued until similarly the back-stop A' is drawn to its elevated or non-playing position. On releasing the cable 52', the frame B' and back-stop A' may be lowered to playing position, the brace-frame C' in like manner automatically latching itself in bracing position, as previously described in connection with the brace-frame C.

36 It will be understood that other changes and modifications in the form, construction, arrangement, and combination of the several parts of the apparatus may be made and substituted for those herein shown and described 35 without departing from the nature and principle of my invention.

Having thus described my invention, what I claim and desire to secure by Letters Patent is:

40 1. In a basket-ball back-stop, a back-stop frame, a swingable brace-frame, and means for detachably connecting the brace-frame to the back-stop frame in playing position, said means including a shaft on the brace-frame 45 for engagement with the back-stop frame, and a bolt shiftable on the back-stop frame for engagement with the shaft.

2. In a basket-ball back-stop, a back-stop frame, a swingable brace-frame, and means 50 for detachably connecting the brace-frame to the back-stop frame in playing position, said means including brackets on the back-stop frame having shaft-seats, a shaft on the brace-frame for seating in said seats, and 55 bolts shiftable on the brackets for retaining engagement with the seated shaft.

3. In a basket-ball back-stop, a back-stop frame, a swingable brace-frame, and means 60 for detachably connecting the brace-frame to the back-stop frame in playing position, said means including brackets on the back-stop frame, said brackets having bolt-ways and 65 shaft-seats tangent to the outer end of said ways, a shaft on the brace-frame for seating in said seats, and bolts yieldingly shiftable in

said ways for retaining engagement with the seated shaft.

4. In a basket-ball back-stop, a swingable back-stop-frame, a swingable brace-frame pivotally connected to the brace-frame, means including a shiftable bolt on the back-stop frame engageable with the brace-frame for latching the frames together in playing-position, and means for actuating the bolt for unlatching the frames for swingable movement thereof to non-playing position, said last means including a rotary shaft on the back-stop-frame, a flexible member having connection with the shaft and the bolt, and a pull-cord for rotarily actuating the shaft.

5. In a foldable basket-ball back-stop, a swingable back-stop-frame, a swingable brace-frame adapted for latchable engagement with the back-stop frame when in playing position, and linkage means permanently connecting said frames pivotally together.

6. In a foldable basket-ball back-stop, in combination with a support, a back-stop frame pivoted to the support, a brace-frame pivoted to the support in spaced relation to the first frame, and linkage hingedly connecting swingable ends of said frames.

7. In a foldable basket-ball back-stop, in combination with a support, a back-stop frame pivoted to the support, a brace-frame pivoted to the support in spaced relation to the first frame, and linkage hingedly connecting swingable ends of said frames, the pivotal point of the back-stop frame being more elevated than the pivotal point of the brace-frame for flatwise disposition of the latter beneath the former when in non-playing position.

8. In a foldable basket-ball back-stop, in combination with a support, a back-stop frame pivoted to the support, a brace-frame pivoted to the support in spaced relation to the first frame, linkage hingedly connecting swingable ends of said frames, and a flexible-member having connection with the support and the back-stop frame for swingably elevating the frames to non-playing position.

9. In a basket-ball back-stop, a swingable back-stop frame, a swingable brace-frame comprising transversely spaced parallel struts and a transverse bar connecting swingable ends of said struts, means including keeper-brackets on said back-stop frame for co-operation with said bar for latching the frames together in playing position, and links pivotally connecting the frames for joint swingable movement and for guiding the brace-frame into latching engagement with the keeper-brackets.

10. In a basket-ball back-stop, a support, a back-stop frame swingably connected to, and normally depending in playing position from, the support, a brace-frame pivotally connected to the support in spaced relation to the first frame, means including a link

5 pivotally connecting said frames permanently together for conjoint swingable movement, and means for separably attaching the second frame at its free end to the first frame when in normal position for securing said frames against swingable movement and the second frame in rigid bracing engagement with the first frame.

11. In a basket-ball back-stop, a support, 10 a back-stop frame swingably connected to, and normally depending in playing position from, the support, a brace-frame pivotally connected to the support in spaced relation to the first frame, means including a link 15 pivotally connecting said frames permanently together for conjoint swingable movement, and means including a slidable bolt for separably attaching the second frame at its free end to the first frame when in normal position for securing said frames against swingable movement and the second frame in rigid bracing engagement with the first frame.

12. In a basket-ball back-stop, a support, 25 a back-stop frame swingably connected to, and normally depending in playing position from, the support, a brace-frame pivotally connected to the support in spaced relation to the first frame, means including a link 30 pivotally connecting said frames permanently together for conjoint swingable movement and means including a slidable bolt for separably attaching the second frame at its free end to the first frame when 35 in normal position for securing said frames against swingable movement, the second frame in rigid bracing engagement with the

first frame, and manipulative means including a pull-cable having connection with the bolt for frame-releasing actuation thereof for permitting swingable movement of the frames. 73

13. In a basket-ball back-stop, a support, a back-stop frame swingably connected to, and normally depending in playing position from, the support, a brace-frame comprising hingedly connected first and second members pivotally connected at its first member to the support in spaced relation to the first frame and permanently connected at its second member with the first frame for conjoint swingable movement with the first frame to non-playing position, and means for detachably securing the second frame also at its first member to the first frame for rigidly bracing the first frame in playing position. 75

14. In a basket-ball back-stop, a support, 25 a back-stop frame swingably connected to, and normally depending in playing position from, the support, a brace-frame comprising hingedly connected first and second members pivotally connected at its first member to the support in spaced relation to the first frame and permanently connected at its second member with the first frame for conjoint swingable movement with the first frame to non-playing position, means including a slidable latch-bolt for detachably securing the second frame also at its first member to the first frame for rigidly bracing the first frame in playing position, and means for actuating the bolt for permitting swingable movement of the frames to non-playing position. 80
